DESIGN FOR A PICTORIAL CHART

Caroline M. Stafford, Portland, Oreg.

Application April 25, 1933. Serial No. 47,896

Term of patent 14 years

To all whom it may concern:

Be it known that I, CAROLINE M. STAFFORD, a citizen of the United States, residing at Portland, county of Multnomah, State of Oregon, have invented a new, original, and ornamental Design for a Pictorial Chart, of which the following is a specification, reference being had to the accompanying drawing, forming part thereof.

The figure is a plan view of the chart showing my new design.

The chart is employed to show graphically how the system of relief operates, namely for building up a relief fund through the sale of stamps to merchants.

I claim:

The ornamental design for a pictorial chart, as shown and described.

CAROLINE M. STAFFORD.
